[57] CLAIM

The ornamental design for an oil fire extinguishing cone, as shown and described.

DESCRIPTION

FIG. 1 is a perspective view of the oil fire extinguishing cone embodying the design of the present invention; FIG. 2 is a front elevational view thereof, the rear being a mirror image of the front shown in FIG. 2; FIG. 3 is a side elevational view thereof, the side opposite being a mirror image of the side shown in FIG. 3; FIG. 4 is a top plan view thereof; and, FIG. 5 is a bottom view thereof.

FIG.1.

FIG. 3.

FIG. 4.

FIG. 5.

FIG. 2.
